UNITED STATES PATENT OFFICE.

ARTHUR CAMERON, OF CHICAGO, ILLINOIS, ASSIGNOR TO NATIONAL DRILL AND MANUFACTURING COMPANY, OF CHICAGO, ILLINOIS, A CORPORATION OF WEST VIRGINIA.

CRUSHING-MACHINE.

No. 802,842.

Specification of Letters Patent.

Patented Oct. 24, 1905.

Application filed August 29, 1903. Serial No. 171,203.

To all whom it may concern:

Be it known that I, ARTHUR CAMERON, a citizen of the United States, residing at Chicago, in the county of Cook and State of Illinois, have invented a certain new and useful Improvement in Crushing-Machines, of which the following is a specification.

My invention relates to crushing-machines in which a reciprocating jaw is arranged to coöperate with a stationary crushing-jaw for crushing rock, ore, and the like, the reciprocating jaw being operated by a pitman, with which it has a jointed connection, and the pitman being controlled by swinging arms or links having jointed connection with the pitman and tied to swing about a transverse axis forward of the reciprocating crushing-jaw.

Objects of my invention are to secure rapid and efficient action, to reduce the power employed for operating the reciprocating crushing-jaw, to produce a grinding crushing action, to provide improved means for varying the distance between the axis about which the arms swing and the axis about which they have a jointed or pivotal connection with the pitman, to balance the reciprocating crushing-jaw in a simple and efficient way, and to provide a generally-simplified construction of crushing-machine.

In the accompanying drawings, Figure 1 is a longitudinal section on a vertical plane through a crushing-machine embodying the principles of my invention. Fig. 2 is a section on line 2^a 2^a in Fig. 1. Fig. 3 is a detail section through a portion of the machine on line 3^a 3^a in Fig. 1. Fig. 4 is a detail section on line 4^a 4^a in Fig. 2. Fig. 5 is a detail section on line 5^a 5^a in Fig. 3.

A indicates the body-frame of the machine, and B denotes the stationary crushing-jaw arranged at what may be termed the "forward" end of the machine. The reciprocating crushing-jaw C is arranged back of and opposite the stationary crushing-jaw and is provided with or secured to a rearwardly-extending arm D, which is, in effect, an arm on the said jaw. The rear end of the jaw-arm D has a jointed or pivotal connection with the pitman E, which is operated by an eccentric 1 on a rotary power-driven shaft, as usual, said shaft being indicated by a dotted line in Fig. 1. The pitman preferably extends upward from the axis of the driving-shaft and is controlled by

swinging arms or links F, having their rear end portions joint-connected with or pivoted 55 to the pitman and having their forward end portions tied to swing about the axis of a horizontally and transversely arranged shaft G at a point forward of the reciprocating crushing-jaw. The reciprocating crushing- 60 jaw is supported to oscillate about a transverse horizontal axis located between the upper and lower portions of the jaw and susceptible of a forward-and-back reciprocating movement during operation, it being understood that this axis is between the upper and lower portions of the jaw or intermediate or substantially intermediate of the upper and lower ends of the jaw, in contradistinction to a crushing-machine in which the lower end of 70 the jaw is sustained by a pivotal support arranged for forward-and-back reciprocating movement.

By arranging the axis about which the jaw oscillates as in this application the jaw can be 75 balanced or substantially balanced so as to be susceptible of easy operation, and to avoid all tendency on the part of its shifting pivotal support to cramp or bind and by thus arranging the jaw to oscillate about such axis 80 in contradistinction to a jaw which vibrates about a pivot at its lower or upper end I am enabled to secure more efficient crushing action upon the material within a hopper or space between the two jaws, the crushing action upon the mass of material between the jaws being rapid and effective and practically continuous. I also permit the axis about which the reciprocating jaw oscillates to reciprocate along an incline which slopes downwardly to- 90 toward the stationary crushing-jaw, whereby a grinding action is attained, and as a matter of further improvement I form said incline along an upward curve arranged to secure the necessary degree of inclination and preferably 95 formed on the arm of a circle having its center below the reciprocating crushing-jaw. As one way in which the reciprocating jaw can be supported to thus oscillate about a reciprocating axis between its upper and lower 100 portions I provide the jaw or, what is the same thing, the back to which the jaw-face is attached with a transversely-arranged horizontal shaft or pivot H, having its end portions supported upon bearings I. These bearings 105 may either form a part of or be detachably

secured to the body-frame, and each of such bearings has its upper surface adapted to provide a curved bearing-face 2, which slopes downwardly toward the stationary crushing-jaw. As shown in Figs. 2 and 4, these bearings 5 are arranged at the lower ends of vertical slots or openings 3 in opposite sides of the body-frame, and with such arrangement the journals or pivots formed by end portions 10 of the shaft H extend through the slots, which are of a width to permit these pivots to reciprocate back and forth upon the inclined bearing-faces 2, it being seen that during operation the pivots or journals formed by the shaft 15 H will also rock upon the inclined bearing-faces 2. It is obvious, therefore, that the reciprocating jaw is, in effect, provided with downwardly-curved bearing-faces, which rock and shift upon the inclines formed by the 20 bearing-faces 2, and that, broadly considered, the bearing-faces 2 are, in effect, a single bearing-face, which is divided into two portions for convenience of construction.

From the foregoing it will be seen that each 25 bearing-surface 2 on the body-frame inclines downwardly and forwardly notwithstanding the fact that they are each curved and that the movable crushing-jaw is provided with bearings supported upon and adapted and arranged 30 to traverse the bearing-surfaces 2.

The rod or shaft G is formed with cylindric end portions 4, constituting pivots or journals upon which forward end portions of the arms F are hung, whereby when the shaft G is held 35 stationary the arms F can turn thereon, and thereby swing about the axis of such shaft. The portion 5 of shaft G extending between its journal portions 4 is enlarged to form an eccentric which engages in a bearing K, secured to the 40 forward portion of the body-frame, as by bolts 6 or by any other suitable mechanical device. As portion 5 of the shaft is eccentric to an axis passing through its journal portions 4, the latter are, in effect, crank or wrist pins 45 upon opposite ends of the main portion 5 of the shaft, and hence by rotative adjustment of the shaft G its axis about which the arms F swing can be adjusted so as to vary the distance between such axis and the axis of the 50 jointed or pivotal connection between the arms and the pitman, it being observed that this variation is essential for different kinds of work.

After the shaft G has been rotatively ad- 55 justed it can be rigidly secured to the bearing K in any suitable way—as, for example, by set-screws 7, arranged to extend through the bearing K and engage in notches or recesses 8 in the shaft. In order to permit the shaft G to 60 be easily adjusted, it can have squared or polygonal end portions 9, which can be engaged by a crank or crank-handle.

The arms F can be pivotally attached to the pitman in any suitable or desired way, and in 65 any suitable or desired way the hinge or piv-

otal connection can be made between the jaw-arm and the pitman, it being preferable to connect the arm D with the pitman at a point nearer the eccentric than is the point of connection between the pitman and the swinging 70 arm F.

What I claim as my invention is—

1. In a crushing-machine, a crushing-jaw supported for oscillatory motion about an axis arranged between its upper and lower portions and reciprocative laterally to the plane of the jaw-face and along a line inclining downwardly and forwardly; a pitman with which the jaw has a jointed connection; and swinging arms or links having jointed connection with the pitman and tied to swing about an axis forward of the said jaw. 75

2. In a crushing-machine, a crushing-jaw supported for oscillatory motion about an axis arranged between its upper and lower portions and reciprocative laterally to the plane of the jaw-face and along a curved line inclining downwardly and forwardly; a pitman with which the jaw has a jointed connection; and swinging arms or links having jointed connection with the pitman and tied to swing about an axis forward of the said jaw. 80

3. In a crushing-machine, a crushing-jaw supported for oscillatory motion about an axis arranged between its upper and lower portions and reciprocative laterally to the plane of the jaw-face and along the arc of a circle having its center below the jaw; a pitman with which the jaw has a jointed connection; and swinging arms or links having jointed connection with the pitman and tied to swing about an axis forward of the jaw. 95

4. In a crushing-machine, a crushing-jaw supported for oscillatory motion about a laterally-reciprocating axis arranged between its upper and lower portions, the jaw being to such end provided with a curved bearing-face supported to rock upon and traverse an inclined supporting-face which slopes downwardly and forwardly; a pitman with which the jaw has a jointed connection; and swinging arms or links having jointed connection with the pitman and tied to swing about an axis forward of the jaw. 110

5. In a crushing-machine, a crushing-jaw having a rear arm rigid therewith and supported for oscillatory motion about an axis arranged between its upper and lower portions and reciprocative laterally to the plane of the jaw-face along a line inclining downwardly and forwardly; a pitman with which the jaw-arm has a jointed connection; and swinging arms or links having jointed connection with the pitman and tied to swing about an axis forward of the jaw. 115

6. In a crushing-machine, a crushing-jaw having a rear arm rigid therewith and supported for oscillatory motion about an axis arranged between its upper and lower portions and reciprocative laterally to the plane 130

of the jaw-face along the arc of a circle having its center below the jaw; a pitman with which the jaw-arm has a jointed connection and swinging arms or links having jointed connection with the pitman and tied to swing about an axis forward of the jaw.

7. In a crushing - machine, a stationary crushing - jaw and a reciprocating crushing-jaw; a pitman with which the jaw has a jointed or pivotal connection; swinging arms or links having jointed connection with the pitman and arranged to swing about a transverse axis forward of the stationary jaw; and an adjustable eccentric device for varying the distance between said axis and the jointed or pivotal connection between the swinging arms and the pitman.

8. In a crushing - machine, a stationary crushing - jaw and a reciprocating crushing-jaw; a pitman with which the reciprocating crushing-jaw has a jointed connection; swinging arms or links having jointed or pivotal connection with the pitman and supported to swing about an axis forward of the stationary crushing-jaw; and an adjustable eccentric device comprising a bearing forward of the stationary crushing-jaw, and a rotatively-adjustable shaft having journal portions upon which the swinging arms are hung and an eccentric portion engaging the said bearing.

9. In a crushing - machine, a stationary crushing-jaw; a reciprocating crushing-jaw arranged opposite the stationary jaw and having a rear arm; a pitman with which said jaw-arm has a jointed or pivotal connection; swinging arms or links having jointed or pivotal connection with the pitman; a bearing on the body - frame forward of the stationary jaw; and a rotatively-adjustable shaft having journal portions upon which the swinging arms are supported, and an eccentric portion intermediate of said journal portions and engaging in said bearing; and suitable means for locking said shaft in its adjustment.

10. In a crushing-machine, the body-frame provided at each of two opposite sides with a bearing - surface inclining downwardly and forwardly; a pitman; a movable crushing-jaw having a jointed connection with the pitman and provided between its upper and lower portions with bearing members supported to traverse and rock upon the said inclined bearing-surfaces on the body-frame; and swinging arms or links having jointed connection with the pitman and tied to swing about an axis forward of said jaw.

ARTHUR CAMERON.
